UNITED STATES PATENT OFFICE.

DAVID PERLMAN, OF NEW YORK, N. Y.

CLOTH-CUTTING MACHINE.

1,173,983.

Specification of Letters Patent. Patented Feb. 29, 1916.

Application filed August 26, 1915. Serial No. 47,396.

To all whom it may concern:

Be it known that I, DAVID PERLMAN, a subject of the Czar of Russia, and resident of New York, in the county of New York and State of New York, have invented certain new and useful Improvements in Cloth-Cutting Machines, of which the following is a specification.

This invention relates to certain improvements in cloth cutting machines of that type in which a reciprocating knife is employed. Machines of various different forms belonging to this type are in general use and well known in the garment manufacturing trade. In all of these machines with which I am familiar, the sharpening of the knife is an operation involving a considerable loss of time, the liability of injury to the operator and to the machine, and usually performed with difficulty and with poor results. This is due partly to the character of the sharpener which is used and partly to the fact that most operators, even though highly skilled in the art of cutting cloth, are not skilled in the art of sharpening the cutting instrument.

To sharpen the knife of most cloth cutting machines of this type, it is necessary to raise the presser-foot and fasten it in raised position. As this presser-foot or the support therefor serves as a guard in front of the portion of the knife edge above the cloth, the raising of the presser-foot and its support exposes the knife edge so that during the sharpening operation, the operator is liable to get his hand on the exposed edge and be seriously injured. The exposed edge is then usually sharpened by a very primitive and impracticable operation. Usually a stick or rod coated with emery or other abrasive material is held in the hand and rubbed lengthwise against the sides of the knife at the edge to be sharpened, the rubbing operation taking place alternately upon opposite sides until the knife becomes sharp. The operator must then return the presser-foot guard to its original position and time is lost in re-adjusting it to exactly the original position and in accordance with the exact height of the layers of cloth being cut. This method of operation not only gives very poor results with a waste of time and danger to the operator, but it also has other disadvantages. The operator must be skilful as the

holding of the sharpening stick at an angle slightly different from the correct one, will result in dulling rather than sharpening the knife. Furthermore, the sharpening operation does not make a perfect bevel throughout the whole length of the knife and ordinarily wears away more of the knife along one portion than at another so that the cutting edge eventually becomes somewhat scalloped. As soon as the knife edge becomes uneven, it must be discarded as it may be the cause of spoiling the cloth. In rubbing the sharpening stick up and down the sides of the knife, a portion of the stick often, and in fact usually, comes in contact with the support for the driving mechanism which stands in the rear of the knife. Thus, the support is worn away by the unnecessary grinding action on the sides thereof. I am aware that certain machines have been designed to overcome some of these difficulties, but none of them with which I am familiar has proven practical or successful and none are in use. By means of my invention, I overcome these various disadvantages and render the sharpening mechanism so easily operated and so nearly automatic in action that the operator cannot very well fail to get satisfactory results. I overcome the disadvantage of raising, lowering and adjusting the presser-foot guard in accordance with the thickness of the goods every time the knife needs to be sharpened. The mechanism is so arranged that after the presser-foot has once been adjusted to the proper position in accordance with the thickness of the layers of cloth to be cut, it may be quickly and accurately returned to this adjusted position after the sharpening operation. In fact I preferably so arrange the parts that the presser-foot cannot lock itself in any other but the correct position.

A further important feature of my improved construction is an arrangement whereby the presser-foot guard protects the knife along its full length and prevents the operator from being injured during the sharpening operation while in other machines the guard is moved to inoperative position and the knife edge exposed before the knife can be sharpened. In order to sharpen the knife with my improved device, all the operator has to do is to lower the presser-foot guard to its extreme bot-

tom position, permit it to remain there a few seconds and then lift it back to its original position where it locks itself automatically in its previously adjusted position. By this simple and quick operation, a pair of grinding stones are caused to start rotating and travel down the length of the knife blade and then back again to the upper end. The stones are so mounted and 5 so operate as to give a perfect cutting edge formed exactly in the plane of the center of the material constituting the knife blade and in a straight line from the top to the bottom. The grinding stones can never 10 swing in contact with the support of the machine and cannot obstruct the view of the chalk or pencil marks on the cloth to be cut. The stones are automatically set in motion to perform the grinding operation and when 15 they have completed the downward and return movement, they automatically stop. The grinding mechanism is so constructed that the stones can be adjusted by anyone without mechanical knowledge by simply 20 loosening the screws which retain the support and slightly rotating the support so as to bring both of the stones at equal distances toward the plane of the cutting edge. The movement of the stones is equal and 25 simultaneous and one single character of adjustment takes care of both the wear on the stones and the wearing away of the knife blade itself. This adjustment is needed only when the stones or knife blade 30 have become materially worn from their 35 original form.

The grinding of the knife may be performed either while the knife is normally working up and down or while the knife is 40 locked in raised position. To accomplish this, I provide means for disconnecting the knife from the source of power and locking it in position at the same time that the grinders are connected to the source of power, the two operations being accomplished by the single movement of a controlling member.

Whether or not the knife is to be ground while reciprocating or while stationary, will 50 depend largely upon the character of edge which is desired and this depends upon the character of the goods to be cut.

To prevent the vibration of the whole of the machine due to the jar caused by the 55 rapid and repeated changes in the direction of movement of the knife, the eccentric, and the connecting parts, I provide a further important feature of my invention. This jar-ring action is the principal cause of the 60 bearings of the motor getting out of order and of the excessive wear in the connecting link, pins, and other parts. In my improved construction I provide a special form of shock absorbing spring cushion in the connecting link which will absorb the jar caused 65

by the sudden changes in the direction of movement of the oscillating parts. I am aware that attempts have been made to overcome this jar by placing rubber cushions or the like underneath the plate and 70 between the latter and the supporting rollers. This does not prevent the vibration of the whole machine and in fact tends to increase the vibration although to a certain extent it relieves the jar. In my improved 75 construction, the cushioning means is disposed between the body of the machine and the reciprocating parts so that the vibration caused by the latter is not transmitted to the body of the machine and the base of the latter 80 may come into direct contact with the table without objectionable jumping of the base which occurs when the cushioning means is placed beneath the latter.

My invention involves various other important features which will be pointed out more particularly hereinafter, but I wish it specifically understood that in describing all of the features embodying my invention, I do not desire to be limited to such specific 90 description.

In the accompanying drawings to which reference is to be had and in which similar reference characters indicate corresponding parts in the several views, I have illustrated 95 only one embodiment of my invention.

Various changes may be made within the scope of my invention as defined in the appended claims and various elements together with their functions may be omitted or used 100 in combination with, or in connection with, other features or in other machines. The specific form shown in the drawings is to be considered in an illustrative rather than in a limiting sense.

In these drawings: Figure 1 is a front view of a machine embodying my invention; Fig. 2 is a side view thereof; Fig. 3 is a vertical section of a portion of the machine substantially in the plane of the knife and on a somewhat larger scale than Figs. 1 and 2; Fig. 4 is a view similar to a portion of Fig. 3 showing the operation of one gear shift mechanism; Fig. 5 is a sectional detail substantially on the line 5-5 of Fig. 4; Fig. 6 is a transverse section substantially on the line 6-6 of Fig. 3; Fig. 7 is a vertical section on the line 7-7 of Fig. 3 and showing the parts in normal position, that is, with the grinder operating mechanism in a raised or inoperative position; Fig. 8 is a section similar to Fig. 7 but showing the grinder operating mechanism in action on the downward movement; Fig. 9 is a section similar to Fig. 7 but showing the grinder operating mechanism in action on the upward movement; Fig. 10 is a vertical section substantially on the line 10-10 of Fig. 3 and with the parts in the position shown in Fig. 3; Fig. 11 is a view somewhat simi- 130

lar to Fig. 10, but showing the grinders in end view and locked in position for operation; Fig. 12 shows a plan and a side elevation of the locking mechanism for holding the presser-foot in raised position; Figs. 13, 14 and 15 each shows two views of parts included in the controlling mechanism and shown in combination in Figs. 10 and 11; Fig. 16 is a sectional detail showing the 10 crank and connecting link for operating the knife, the parts being shown on somewhat larger scale than in Fig. 3; Fig. 17 is a face view of the parts shown in Fig. 16; Fig. 18 is a view similar to a portion of Fig. 16, 15 but showing the crank disconnected from the drive shaft; Fig. 19 includes face and edge views of the knife operating crank; Figs. 20, 21 and 22 each show two views of the clutch mechanism of Figs. 16 and 17; Fig. 23 is a transverse section on the line 23—23 of Fig. 3; Fig. 24 is a face view of the parts shown in Fig. 23; Fig. 25 is a side elevation of one grinder stone and the supporting and driving parts; Figs. 26, 27, 20 25 28 and 29 each show two or more views of the parts for supporting, driving and adjusting the grinder stones, said parts being shown in combination in Fig. 3; Fig. 30 is a detail showing the parts for starting the 30 grinders in operation upon the lowering of the presser-foot support and guide. Fig. 31 is a view similar to Fig. 30, but showing the parts in maximum lowered position; and Fig. 32 is a top plan view of a portion of 35 Figs. 1 and 2.

I have illustrated one embodiment of my invention as applied to a machine having certain features in common with other machines of the same type to which my invention is particularly applicable. The machine in its main essentials includes a plate or base 40 adapted to rest upon the table and move along the latter beneath the goods to be cut. A standard 41 is rigidly secured 40 to and extends upwardly from this base and carries at its upper end an electric motor 42 or any other suitable source of power. The motor may have any suitable form of terminals 43 to which electric 45 wires may be connected and the frame or casing of the motor may have a handle 44 by means of which the entire machine may be moved along the platform and guided so that the knife will follow the desired line upon the cloth or other goods being cut. A knife 45 is mounted to move vertically directly in front of the standard 41 and is preferably guided by the latter. The base 50 may have an opening 46 into which the lower end of the knife may enter when in its lowered position and may have rollers 47 or other anti-friction devices for facilitating the movement of the base over the table. These features in their general arrangement and broad combination consti-

tute no portion of my invention although my invention does embody certain features of construction of certain of these parts.

Knife guard and adjusting mechanism therefor.—In order to protect the operator 70 and prevent him from at any time getting his hand on the knife, I provide an improved form of guard which does not need to be removed from in front of the knife at any time and which must be in proper 75 guarding position when the knife is being sharpened. In the specific form illustrated, this guard is in the form of a tube 48 mounted for vertical movement directly in front of the cutting edge of the knife and 80 substantially parallel to said cutting edge. This guard has a presser-foot 49 on its lower end which is adapted to rest upon or engage with the upper surface of the goods during the cutting operation. The combined 85 guard and presser-foot 48 is supported at its upper end and telescopes within a tubular casing 50 rigid with the frame of the machine. As shown particularly in Fig. 2, this casing extends for a considerable 90 distance above the motor and is connected to the frame not only at its lower end, but by means of a bracket or brace rod 51 engaging with the casing intermediate of the 95 ends of the latter.

The guard may be raised or lowered dependent upon the thickness of the goods being cut and may be locked in the desired adjusted position. The guard 48 serves not only to carry the presser-foot and to protect the knife, but also serves as a guide for the grinding mechanism so that the latter may slide up and down the guard while grinding the knife. The guard is so constructed that its lower end may be brought 100 adjacent to or into engagement with the base 40 and may be locked at its lower end so as to make it more rigid during the grinding operation. It must of course be spaced from the base during the cutting 105 operation as the cloth passes therebeneath before reaching the knife. After the guard has once been set for cuts of a definite thickness, it may be lowered and locked to the base while the knife is sharpened and 110 when again raised after the sharpening operation has been completed, it will automatically lock itself in the original position and avoid the necessity for readjustment. This supporting, locking and adjusting mechanism is shown particularly 115 in Figs. 10 to 15 inclusive.

The tubular casing 50, within which the guard 48 slides, is rigidly secured to a bracket 52 which latter is rigid with the 120 main frame of the machine. The guard may be locked to the tubular casing 50 in any desired longitudinal adjustment and within the guard 48 is a third telescoping member 53 which, when moved downwardly 125

in respect to the guard, will enter a socket member 54 in the base. This inner rod 53 normally has its lower end substantially flush with or at least not projecting below the lower surface of the presser-foot as is shown particularly in Figs. 3 and 10. It is normally held in this position by the mechanism about to be described.

The guard 48 has a flange or plate 55 rigid therewith and projecting outwardly from one surface thereof substantially as shown in Fig. 13 and within this plate are two vertically extending, substantially parallel slots 56 and 57. The plate or flange 55 is mounted between two plates 58 and 59. These may be separate and rigidly connected in any suitable manner or they may be the side portions of a metal block with a deep groove cut therein as shown in Fig. 14. Transverse pins 60 extend from one plate to the other and project through the slots 56 and 57. The distance between the pins is less than the length of the slots so that the plates 58 and 59 may have a vertical sliding movement on the plate 55.

The guard 48 has a longitudinally extending slot therein just below the plate 55 and out through this slot extends a pin 61 rigidly connected to the inside rod 53. The two plates 58 and 59 have opposed recesses or grooves which receive the pin 61 whereby any longitudinal movement of the said plates 58 and 59 is accompanied by a corresponding endwise movement of the rod 53.

For purposes of assembly or repair, the pin 61 is preferably threaded into the rod 53 and the recesses in the plates 58 and 59 are such that the pin may be unscrewed and removed endwise when desired.

At the lower end of the slot in the guard 48, I provide an outwardly extending lip or flange 62 serving as a guide for a pin 63 and has an abutment for a small coil spring 64. The upper end of the pin 63 may, if desired, be screwed into the side of the pin 61 and the upper end of the spring may engage with the pin 61 or with the lower ends of the plates 58 and 59. The spring is of such size and strength that it normally lifts

the pin 61 to the maximum distance and holds the two upper pins 60 at the upper ends of the slots 56 and 57. With the parts in this position, the lower end of the rod 53 will be flush with or withdrawn into the

lower end of the guard 48 as shown in Fig. 10. In the normal operation of adjusting the presser-foot in accordance with varying thicknesses of the cloth, the inner rod 53 and the guard 48 will move together and the parts will retain the same relative positions, as is shown in Fig. 10.

For holding the guard and presser-foot at the proper elevation, I employ clamping or locking mechanism capable of disengagement at two separate points. This includes

a slide 65 mounted for vertical movement on the tubular casing 50 and adapted to be detachably connected to said casing and also detachably connected to the guard. For detachably connecting the slide to the stationary tubular casing, I provide the latter with a series of recesses, apertures, or teeth, along its opposite sides and provide the slide 65 with one or more pawls or dogs adapted to coöperate with said recesses, apertures or teeth. As shown, the slide 65 has two pawls or dogs 66 pivoted thereto upon the upper surface and mounted to swing in a horizontal plane. The outer ends of these pawls or dogs are normally spread apart by a spring 67 and the opposite ends engage with the teeth or recesses in the sides of the tubular casing. By pressing the outer ends of the dogs together, the inner ends will be released and the slide 65 may be moved up or down to the desired adjusted position. To provide a more delicate adjustment, the recesses on one side of the casing 50 are opposite to the spaces between the recesses on the opposite side so that never will more than one of the dogs engage with the casing so as to lock the slide in position.

For detachably connecting the guard 48 to the slide 65, I provide a suitable spring pressed catch. As shown this includes a yoke part 68 adapted to engage with opposite sides of the plates 58 and 59 and pivotally supported on the projecting ends of the pins 60 which extends through the slot 56. At the outer end of the yoke is an upwardly extending hook 69 adapted to engage with a shoulder on the slide 65. Thus, when the slide 65 is moved up or down on the tubular casing 50, it will carry with it the hook 69, the plates 58 and 59, the pin 61 and the inner rod 53. The tubular guard 48 will be carried along with the rod by reason of the flange or plate 55, and the engagement of the latter with the pins 60. Thus, the presser-foot may be very quickly raised or lowered and locked in an adjusted position by merely grasping the outer ends of the two catches 66, pressing them together, and raising or lowering them.

When it is desired to grind the knives, the guard 48 is used as a guide upon which the grinding mechanism may slide as has been previously stated. During the grinding operation, the presser-foot is lowered into engagement with the base and the rod 53 is moved down still farther, and out of the lower side of the presser-foot into the recess 54 of the base to lock the lower end of the guard against sidewise movement. To hold the parts in this position I provide a second catch member somewhat similar to the catch member last described and which is shown in detail in Fig. 15. This catch member includes a yoke part 70 adapted to engage with the opposite sides of the plates 58 and 59.

and 59 and pivotally secured upon the lower pin which passes through the outer slot 56 of the plate 55. Depending from the yoke is a hook part 71 adapted to engage beneath 5 a shoulder in the bracket 52 or other stationary part of the machine. To prepare the machine for the grinding operation, the handle portion of the hook 69 is depressed so as to disengage the hook from the slide 10 65 and the guard 48 and rod 53 are lowered until the catch 71 engages with the shoulder of the bracket 52, as shown in Fig. 11. Before it reaches this position, the presser-foot 15 49 will have engaged with the upper surface of the base 40. Further movement of the guard 48 and the plate or flange 55 is then impossible. By pressing down on the handle portion of the hook 69, the plates 58 and 59 will be lowered against the action of the 20 spring 64 and the rod 53 will be moved downwardly in respect to the guard and into the socket 54. When the hook 71 engages with the shoulder on the bracket 52 as shown in Fig. 11, the lower end of the rod will project into the base and the spring 64 will be 25 under compression. The grinding operation may now be carried on as will be pointed out more particularly hereinafter. When the grinding operation is completed, the catch 30 71 may be disengaged and the spring 64 will lift the rod up out of the base 40. By merely lifting up on the handle of the hook 69, said hook will be disengaged and the guard and presser-foot will be raised until the hook 35 69 automatically engages with the slide 65. The presser-foot will then be in the exact position from which it was removed prior to the grinding operation. Thus the presser-foot automatically comes back to the same 40 identical position that it occupied before the grinding operation began and readjustment is unnecessary.

Grinders and carriers therefor.—For grinding the knife, I provide two stones 74 45 preferably of frusto-conical form and mounted to rotate about horizontal axes upon opposite sides of the knife blade. Each grinder stone 74 is mounted on a shaft 75 which latter has a driving pinion 76 as 50 shown in detail in Fig. 25. The two shafts are journaled in a circular plate 77 which latter has lugs or shoulders 78 extending out from one surface thereof and including the bearings for the shafts 75. This plate is 55 shown particularly in Fig. 27. The outer surfaces of the two lugs or shoulders 78 are concentric with the plate and serve as bearings for supporting the latter. A slide 79, shown particularly in Fig. 29, has a vertical 60 passageway 80 therethrough whereby the slide may move vertically on the guard 48 and be guided thereby. The guard is non-circular in cross section and in fact preferably rectangular so that the slide 79 cannot 65 turn about the axis of the guard as a center but can only move vertically thereon. Within the passageway 80 I may provide any form of anti-friction bearings such as rollers or balls. At the lower end of the passageway 80 are two curved arms 81 which 70 receive the lugs 78 and provide bearings for said lugs whereby the plate 77 may be rotated about its horizontal axis. For locking the plate in adjusted position in respect to the slide 79, the curved arms 81 are preferably provided with slots 82 through which may extend set screws 83 carried by the lugs 78. The lugs are thus held between the curved arms 81 and upon opposite sides of the passageway 80 so that the guard 48 may 80 move vertically between the lugs 78. The grinder stones come adjacent to the outer ends of the lugs 78 and at one side of the slide 79, while the pinions 76 come adjacent to the opposite surface of the plate 77. 85

For simultaneously rotating the pinions and grinders in opposite directions, I provide a gear wheel 84 shown particularly in Fig. 26. This gear wheel has an annular recess or chamber 85 in one end thereof 90 adapted to receive the body portion of the plate 77 so that the latter may constitute a bearing or support for the gear wheel. Intermediate of its ends, the gear wheel has a series of internal gear teeth 86 adapted to 95 mesh with the two pinions 76 which have their axes eccentric in respect to the axis of the gear wheel 84. This arrangement of the pinions within the gear is clearly shown in Figs. 3 and 24. For holding the gear on its 100 supporting plate 77, any suitable retainer may be employed. As shown, I employ a flange threaded collar 87 shown particularly in Fig. 28. This collar has threaded engagement with the exterior of the gear wheel 86 105 and its flange engages with the outer surface of the plate 77. The collar may be locked so that it cannot become accidentally unscrewed, by means of a set screw as shown in Fig. 3. 110

The gear wheel 84 has a second series of gear teeth 88 arranged on a bevel on the end opposite to the recess 85 and these are designed to mesh with a bevel pinion 89 mounted on a shaft 90 journaled in an opening 91 115 in the slide. The shaft is held against longitudinal movement in respect to the slide so that by moving the shaft longitudinally, the slide 79 may be moved up and down the guard and power may at all times be transmitted from the shaft 90 through the pinion 89, gear teeth 88, gear teeth 86 and pinions 76 to the grinders. These grinders, as previously stated, are disposed upon opposite sides of the plane of the knife 45. In the 120 specific form illustrated in the drawings, these grinders have their axes substantially horizontal and at right angles to the direction of movement of the knife. It is of course evident that this particular angu- 125 130

larity is not essential and that the axes of the grinders may extend at various different angles in respect to the vertical. If their axes are not horizontal, a corresponding change would of course be made in the inclination of the faces of the gears 88 and 89. They are also preferably frusto-conical in form. With the plate 77 rotated to bring the axes of the shafts 75 on the same horizontal plane, the two grinders will be at a maximum distance from the plane of the knife blade. By loosening the set screws 83 and rotating the plate 77 in the slide 79, one shaft 75 will be raised and the other lowered and at the same time the two grinders will be brought toward the plane of the knife. Thus, as the grinders wear away, they may be readjusted so as to properly engage with the knife and likewise as the knife wears away, the same character of adjustment will bring the grinders into proper operative position, due to their frusto-conical form.

Grinder driving, raising and lowering mechanism.—Directly above the slide 79 I provide means for rotating the shaft 90 and simultaneously moving it endwise. This mechanism includes an automatic governor whereby the endwise movement of the shaft 90 will carry the slide down until the grinders reach the lower end of the knife and will then automatically reverse and raise the slide until the grinders are above the upper end of the knife. The power transmitting mechanism is then automatically disconnected with the slide in its original raised position and with the grinders above and out of the path of the knife. This mechanism is shown particularly in Figs. 7, 8 and 9, while its connection to the source of power is shown in Fig. 3.

Rigidly connected to or integral with the main frame of the machine is a bracket 93 constituting a support for the shaft 90 and a casing for the gears, whereby the shaft 90 is rotated. The shaft 90 is of a length somewhat greater than the range of movement of the grinders. It is threaded throughout the whole or a major portion of its length and engages within an internally threaded passageway through the bracket 93 so that any rotation of the shaft 90 is accompanied by a corresponding endwise movement. The pitch of the threads is comparatively small so that the endwise movement is slow as compared to the speed of rotation. Mounted within the bracket 93 is a gear wheel 94, in the form of an annulus or ring, having an internal set of gear teeth 95 and a set of beveled gear teeth 96 at one end. The gear wheel 94 is eccentric in respect to the shaft 90 but encircles the same and the shaft 90 carries a pinion 97 which may mesh with the internal gear teeth 95. The pinion 97 is slidable length-

wise of the shaft 90 irrespective of the threads on the latter but is held against rotation in respect to the shaft by a suitable key engaging in a keyway cut lengthwise of the shaft. ⁷⁰

Parallel to the shaft 90 is a rod 98 which has a pinion 99 rigidly secured thereto. The pinion 99 meshes with the pinion 97 and is kept at all times in mesh therewith by means of arms 100 journaled on the rod 75 98 and engaging with the upper and lower sides of the pinion 97. Thus as the rod 98 is moved endwise, it will carry the pinions 99 and 97 endwise and without rotation of either the shaft 90 or the rod 98. The pinion 97 is normally disposed above the gear wheel 94 as is shown in Fig. 7 and the pinion 99 is of such size that it never intermeshes with the internal gear teeth 95, but may freely slide through the gear wheel 94 ⁸⁰ 85 without contacting therewith.

Rigidly secured to the rod 98 at a short distance above the pinion 99 is a second and slightly larger pinion 101 which is of such size that when the rod 98 is moved endwise ⁹⁰ to the proper extent, the said pinion 101 may mesh with the internal gear teeth 95. By means of the pinions 97, 99, and 101, the shaft 90 may be rotated in either direction from the gear wheel 94. The latter is ⁹⁵ driven in any suitable manner as, for instance, by means of a bevel pinion 102 meshing with the bevel gear teeth 96.

The transmission of power from the gear wheel 94 to the shaft 90 is accomplished substantially as follows: The parts normally occupy the position indicated in Fig. 7 and the gear wheel 94 may freely rotate without the transmission of power to the shaft 90. When it is desired to grind the knife, the rod 98 is moved endwise, either manually or automatically, as will be hereinafter pointed out, and the pinion 97 is brought into mesh with the internal gear 95. The parts will then occupy the position indicated in Fig. 8 and the shaft 90 will be rotated in the same direction as the gear 94. The pinions 97 and 99 remain in the same plane while the rotating of the shaft 90 causes it to move endwise and lower the grinder carrier and grinders and cause the grinders to be rotated and engage with the knife. When the grinders reach the lower end of the knife, the rod 98 is depressed still further, that is, to the position shown in Fig. 9. Now the pinion 101 will mesh with the internal gear 94 to rotate the rod and the rotation of the latter will transmit motion to the shaft 90 through the pinions 99 and 97 and cause the shaft 90 to rotate in the opposite direction ¹¹⁵ to that of the gear 94. This will screw the shaft 90 back and raise the grinders upwardly along the knife. It will be noted that the grinders operate equally well irrespective of their direction of rotation and ¹²⁰ ¹²⁵ ¹³⁰

any upward or downward movement of the slide carrying the grinders will be accompanied by a corresponding rotation of the grinders. Due to the fact that the gear 5 wheel 84 is materially larger than the grinders, the latter will rotate at a speed materially greater than that of the shaft 90.

Automatic gear shifter for raising and lowering the grinders.—Although in some 10 constructions I may operate the rod 98 by hand, I preferably employ automatic mechanism for depressing the rod 98 to its lowermost position when the grinders reach the lower end of the knife and automatically 15 raise it to its highest position and disengage the gears when the grinders have completed their upward or return movement along the knife blade. One form of such mechanism is shown particularly in Figs. 7 to 9 inclu- 20 sive.

The shaft 90 and the rod 98 extend to a considerable distance above the gear casing or bracket 93 and on these upwardly projecting ends is mounted the automatic controller 25 for effecting the shifting of the gears. The shaft 90 has two collars 103 and 104 rigidly secured thereto. The collars are preferably threaded on the shaft so that they may be axially adjusted to the proper position and 30 they are provided with set screws or other locking means for holding them against any accidental rotation in respect to the shaft after they are once adjusted to the proper position. The lower collar 103 has a beveled 35 or frusto-conical lower end 105 and an annular flange 106 at its upper end, while the upper collar 104 has an annular flange 107 at its lower end and a frusto-conical upper end. The rod 98 has two collars 109 and 110 40 rigidly secured thereto and between these collars are two collars 111 and 112 each capable of movement lengthwise of the rod. A coil spring 113 tends to keep the collar 111 spaced at a predetermined distance above 45 the collar 109 and a coil spring 114 normally presses the collar 112 downwardly from the collar 110 and against a stop 115. Each of the collars 109, 110, 111, and 112 have outwardly extending annular flanges thereon, 50 the flanges of the two collars 111 and 112 being adapted to engage with the flanges of the collars 103 and 104. The flange of the collar 111 is always below the flange 106 and the flange of the collar 112 is always above the 55 flange 107.

The collars and springs are preferably enclosed within a casing 116 and adjacent to the upper and lower ends of this casing are two pivoted dogs 117 and 118. The dogs 60 have limited swinging movement in respect to their supports and are so designed as to act as stops for certain collars and be tripped by other collars. The lower dog 117 has one end normally projecting into the path of the flange on the collar 109 so that it acts as

a stop for said collar and limits the downward movement of the rod 98. The opposite end of the dog 117 lies in the path of the conical end 105 of the collar 103 so that as the collar 103 moves downwardly, it will swing the dog out of the path of the flange on the collar 109 and permit further endwise movement of the rod 98. The dog 118 likewise acts as a stop to limit the upward movement of the collar 110 until the upward movement of the collar 104 causes the conical end 108 to tilt the dog 118 and release the collar 110.

The operation of this automatic controller is substantially as follows: With the parts 80 in the position shown in Fig. 7, the operator may press down on a button 119 at the upper end of the rod 98 until the parts come to the position shown in Fig. 8. He is prevented from pushing the rod 98 past this position as the collar 109 engages with the dog 117. At this time, the gear 97 will come into mesh with the gear 94 and the stones will begin rotating and will begin their downward movement. This endwise movement of the shaft 90 will cause the collar 103 to engage with collar 111 and compress the spring 113. The parts are so adjusted that when the grinders reach their lowermost position, the spring 113 will be under compression and the conical end 105 of the collar 103 will engage with the dog 117 to tilt the latter and release the collar 109. The instant the collar 109 is released, the spring 113 will force said collar downwardly 90 and as the collar 109 is rigid with the rod 98, the latter will be moved downwardly and the gears will be shifted. The parts will then be in approximately the positions indicated in Fig. 9. As the shaft 90 begins rotating in the opposite direction, the collars 103 and 104 will move upwardly but the collar 110 will be prevented from moving upwardly due to the fact that it is now below the catch 118. The collar 104 in its upward movement will engage with the collar 112 and press the spring 114 until the conical end 108 of the collar 104 engages with and releases the catch 118. At the time of this release, the spring 114 will be under compression and therefore the collar 110 will 95 instantly move upwardly to the limiting position which carries the rod 98 from its lowermost position, as shown in Fig. 9, up to its uppermost position, as shown in Fig. 7. 100 The gears will now be out of mesh and the shaft 90 and grinders will cease rotation with the grinders above and out of the path of the knife.

In order to better insure the retention of 125 the rod 98 in its various adjusted positions, any suitable means may be employed. I have illustrated the rod 98 as being provided with a series of recesses 120 and have shown a spring pressed ball which may 130

enter the opposed recesses when the rod is moved endwise to the desired position. These recesses are so positioned and the spring behind the ball is of such tension that the rod is held steady in any one of its three positions to which it may be moved. The spring ball does not prevent the rod from being readily moved endwise by hand or by the springs 113 and 114 as above described. It will be noted that all the operator has to do is to press the button downwardly as far as it will go, which will merely bring it to the intermediate position. No further action is necessary as the rod will be automatically moved to the lowermost position when the grinders reach the lower end of the knife. This automatically shifts the gears and starts the upward movement of the grinders and when they reach their uppermost position, they are automatically disengaged and the parts are stopped in their original position. No skill or expert knowledge of any kind is required on the part of the operator as the initial pressing of the button is all that is required.

Control of gears from the grinder guide.—In order to transmit power from the motor to the gear 94, I provide a suitable gear train. This may, under some circumstances, be so designed as to remain continuously in mesh and the gear 94 continuously rotate even though the grinding operation is not being carried on, but preferably I provide means for disconnecting the power between the motor shaft and the gear 94 except when it is desired to operate the grinder.

As shown, the bevel pinion 102 is mounted on a shaft 124 which latter has a pinion 125 keyed thereto and slideable thereon. This pinion is normally in the position indicated in Fig. 3, but may be moved endwise so as to come into mesh with a gear 126 mounted on the main shaft 127 of the motor. A suitable gear shifting device is provided which is automatically operated upon the lowering of the presser-foot into engagement with the base and the lowering of the rod 53 into the base so as to hold the presser-foot and permit the guard to serve as a rigid guide for the grinder. This automatic connection is illustrated particularly in Figs. 4 and 5. A bell-crank lever 128 is pivoted on a bracket 129 and has one end 50 in the form of a yoke 130 engaging with a collar connected to the pinion 125. The opposite end of the lever 128 has two arms 131 and 132 disposed adjacent to one side of the guard 48. Either the guard 48 or the rod 53 has a pin 133, shown particularly in Fig. 5, which may pass the end of the arm 132 and engage with the arm 131 to swing the lever and shift the pinion into mesh with the gear 126, as is shown particularly in Fig. 4. The pin is so positioned

that the lever is not swung until the presser-foot nearly reaches the base. As the lever swings, the upper arm 132 passes over the pin so that as the guard is again raised, the pinion will be moved out of mesh and when the parts reach the position shown in Fig. 3, the pin is free from the lever and may continue to move upwardly as far as desired.

In order to normally lock the gear shift lever 128 in normal position, I provide a spring 134 which has an opening or recess therein adapted to receive a pin 135 on the lower arm 131 of the gear shift lever. Thus, when the parts are in the position shown in Figs. 3 and 5, the gear shift lever is locked against movement. Either the end of the pin 133, or the upper end of the spring 134, or both, are beveled so that as the pin passes the end of the arm 132 and approaches the arm 131, it will engage with the spring and press the latter back and release the pin 135 so that the arm 131 may move downwardly.

In operation, it will be noted that the lowering of the presser-foot to the base and the locking of it in position automatically shifts the pinion into mesh and the return or upward movement of the presser-foot automatically moves the parts out of mesh. The gear shift lever is normally locked but is unlocked at the instant it is desired to move it and the guard may be adjusted to lock the presser-foot in any desired position, except the lowermost position, without operating the gear shift lever.

The machine may be so built that two separate operations are necessary to start the grinders in action; first, the lowering of the presser-foot guard to the base and the locking of it in position, and second, the pressing down on the button 119 to bring the pinion 97 into mesh with the gear 94. It will be noted that if the operator endeavors to perform the second operation before performing the first, no damage will be done and the grinders will not be started. This is due to the fact that the transmission of power is broken between the pinion 125 and the gear 126 until after the presser-foot has been lowered and locked. Therefore, it is immaterial which of the two operations is performed first, although preferably the presser-foot should be lowered before the pinion 97.

In order to avoid the necessity for performing two separate operations to start the grinders, I may provide means for automatically shifting the pinion 97 into mesh upon the lowering of the presser-foot and the locking of it in position. I have illustrated such an automatic controlling device in Figs. 2, 30 and 31.

The guard 48 at its upper end is provided with a slot in one side out through

which extends a bracket 138 rigid with the rod 53. This bracket carries a pivoted dog 139 which is adapted to engage with the rod 98 or with the button 119 on the latter. 5 Thus, as the rod 53 is lowered to its extreme position, it will engage with the button 119 and depress the rod 98 and bring the pinion 97 into mesh. In order to permit the return movement of the rod when 10 the gears are shifted to raise the grinders, I provide an automatic release for the dog 139. As shown, a pin 140 is mounted to slide vertically in the bracket 138 and it has an enlarged portion normally engaging with 15 the end of the dog 139 to prevent the swinging movement of the latter as is shown in Fig. 30. A spring holds the pin in this locking position but when the rod 53 approaches its extreme lower position, it engages with a stop 141 on the casing 116 and 20 lifts the enlarged portion of the pin 140 out of the path of the dog 139. The button 119 and rod 98 may now freely move upwardly at the instant the collar 104 swings 25 the dog 118 and releases the collar 110 as is shown in Figs. 7 to 9 inclusive. These parts are so positioned that the button 119 will be depressed to bring the gears into mesh and to permit the spring catch 121 to 30 enter the middle recess 120 at substantially the same time that the pin 140 strikes the stop 141 and releases the dog 139. The dog 139 is normally held in operative position by a spring 143 and the side of the button 35 119 is of such length that the dog 139 can never get beneath the button. As soon as the presser-foot rod 53 is raised, the dog 139 swings back into the position shown in Fig. 30, and the locking pin 140 also returns to locking position. 40

Knife operating mechanism.—The main shaft 126 of the motor is provided with link mechanism whereby the knife 45 may be reciprocated upon the rotation of the shaft. As I have previously pointed out, I may in some machines desire to lock the knife against reciprocation while it is being sharpened and in others I may desire to permit the knife to continue reciprocating 45 during the sharpening operation. This will depend in part upon the character of the edge which it is desired to produce on the knife and the character of the material to be cut. The machine may be so constructed that the knife will always reciprocate while being sharpened or it may be so designed that the automatic connecting of the grinders to the source of power automatically disconnects the knife from the source of power, or means may be provided within 50 the control of the operator for permitting the knife to operate or locking it against operation, as desired.

In the specific construction illustrated 55 particularly in Figs. 16 to 22 inclusive, the

shaft 127 is provided with a crank 145, the latter having a crank pin 146 and a counter-balancing weight 147. The knife is rigidly secured to a slide 148 held in guides or a dove-tail groove in the frame of the 70 machine and this slide is connected to the crank pin 146 by a connecting link which, in some constructions, might be a single piece, but which is illustrated as embodying a further feature of my invention, and as 75 including two sections 149 and 150.

The crank 145 encircles the end of the shaft and is detachably locked thereto. The locking mechanism includes two collars 151 and 152 spaced apart to hold the crank 80 therebetween and both held against rotation in respect to the shaft. The collar 152 extends across the end of the shaft and this collar has openings 153 therethrough adapted to receive lugs or projections 154 on an 85 end plate 155. This plate is carried by a rod 156 extending lengthwise through the shaft whereby the plate may be moved toward and from the end of the collar 152 and may be rotated in respect to the latter and 90 the shaft 127. Any suitable means may be provided for reciprocating and rotating this rod, but preferably it has a head 157 at the opposite end of the shaft 127 and a coil 95 spring 158 engages with this head and with the end of the shaft to normally tend to move the plate 155 toward the collar 152. The shaft 127 has two or more apertures 160 in the portion of the peripheral surface encircled by the crank and the crank has 100 similar apertures 161 in its inner or bearing surface.

The collar 152 is locked to the shaft as, for instance, by means of a pin 162 so that its apertures 153 register with the apertures or recesses 160 in the shaft and the crank may be rotated so that its apertures or recesses 161 register radially with those of the shaft and axially with those of the collar 152. When the parts are in this position, the projections 154 of the plate 155 may pass through the apertures 153 and each lies partly in one of the apertures 160 and partly in one of the apertures 161 so as to positively lock the crank against rotation. When the parts are in this position, as shown in Fig. 16, the crank will be forced to rotate with the shaft and the knife may be reciprocated. 110 115

When it is desired to stop the knife but 120 permit the shaft to continue rotating, the rod 156 may be moved endwise and rotated through a part of a revolution so that the projections 154 may engage with the outer surface of the collar 152 but out of alignment with the apertures of the latter. I may, if desired, provide the outer collar with shallow grooves 163 in its outer surface to receive the ends of the projections 154 and retain the plate and its projection 125 130

in non-locking position. With the parts in this position, the shaft may freely rotate without moving the knife and the knife may be freely reciprocated independently of any 5 rotation with the shaft.

I preferably lock the knife against reciprocation and hold it in its raised position so that it cannot move while being sharpened. A simple means for accomplishing 10 this result involves the provision of a locking pin or stud 164 on the outer surface of the end plate 155. The link section 150 may be provided with a recess, as shown particularly in Fig. 16, so that when the knife is 15 raised and the crank is on upper dead center, the rod 156 may be pushed in to simultaneously unlock the crank from the shaft and lock the crank and link rigid in respect to each other. The knife cannot now be 20 reciprocated as any reciprocation would necessitate a lateral movement of the portion of the link which receives and is locked by the pin or stud 164.

In order to prevent the jarring or shaking 25 of the body of the machine by the rapid reciprocation of the knife, I provide means for taking up this jar intermediate of the crank and the knife. This means includes cushioning devices which may be constructed in various different ways and may be mounted at any desired points in the transmission connection. Preferably, they are placed as near to the crank as convenient and therefore in the link rather than in 30 the slide 148.

As shown, the link section 150 has a recess in its outer surface into which projects an angular terminal portion or head 166 and the other line section 149. This terminal portion is materially narrower than the recess into which it extends and in the remaining space above and below the surface of said terminal portion, I provide cushions 40 167. Thus, the link section 149 may have a limited but cushioned endwise movement in either direction from a central position in respect to the link section 150. Any suitable guides may be provided for limiting or restricting this movement such for 45 instance as two parallel pins 168 passing through the head 166 and entering the upper and lower surfaces of the recess into which this projection extends. The cushions may be of any suitable character, but are preferably double-leaf springs and of a width approximately equal to the width of the link 55 sections as shown particularly in Fig. 17.

In order that the grinders may not interfere with the link, slide, or other connecting and driving parts for the knife, I provide an improved form of knife substantially as shown in Fig. 2. The knife has a substantially straight blade portion throughout the cutting length of the knife,

but at its upper end it has an offset portion 65 170 in the plane of the blade, but extending upwardly and rearwardly from the cutting edge. This offset portion 170 is disposed sufficiently far in the rear of the cutting edge itself so that it may be rigidly bolted 70 or locked to a lug 171 on the slide 148 and the cutting edge of the knife will come entirely in front of said lug and in front of the link section 149. Thus, the grinders may be moved upwardly to a position above 75 the limiting position of the upper end of the cutting edge of the knife, but will not be in any way interfered with by or come in the path of the slide, the link section 149 the connections between them, or the connections with the knife.

I wish to again emphasize the fact that the specific machine illustrated in the drawings and which has been described in detail is only one form which my invention may 85 assume. Substantially all of the details may be varied without departing from the spirit of my invention and various features, together with their functions, may be entirely omitted and other features radically 90 redesigned. The specific construction of substantially all of the various parts may be materially changed in adapting my invention to various makes of reciprocating-knife cloth cutting machines.

Having thus described my invention what I claim as new and desire to secure by Letters Patent is:

1. A cloth cutting machine including a reciprocating knife, a rotatable grinder 100 adapted to engage therewith and a unitary means for simultaneously rotating said grinder and advancing the same along the length of said knife.

2. A cloth cutting machine, including a 105 knife, a grinder, a source of power, means operated thereby for rotating said grinder, and means also operated from said source of power for moving said grinder along the length of the knife during the grinding 110 action.

3. A cloth cutting machine including a vertically disposed cloth cutting knife, a source of power, means connected thereto for reciprocating said knife, a grinder, means 115 operated from said source of power for moving said grinder up and down along the edge of the knife, and means automatically operated during said up and down movement for rotating said grinder independently of its engagement with the knife.

4. A cloth cutting machine including an electric motor, a knife, a pair of grinders disposed upon opposite sides of the plane of said knife, a carrier for said grinders, connections between said motor and said carrier for moving the latter in the direction of the 120 length of the knife, and means mounted on

5. A cloth cutting machine including a knife, a pair of grinders mounted for simultaneous engagement with the knife, a carrier therefor movable in the direction of the length of the knife, and means for adjusting said grinders on said carrier and toward and from the plane of the knife.
10. 6. A cloth cutting machine including a knife, a pair of grinders mounted for simultaneous engagement with the knife, a carrier therefor movable in the direction of the length of the knife, means for adjusting said grinders on said carrier and toward and from the plane of the knife, and means for rotating said grinders irrespective of their adjusted position.
15. 7. A cloth cutting machine including a knife, a member movable in the direction of the length of the knife, and a pair of grinders rotatable about substantially parallel axes and adapted to engage with opposite sides of said knife and carried by said member, said member being rotatable about an axis intermediate of the axes of said grinders for simultaneously adjusting them toward and from the plane of the knife.
20. 8. A cloth cutting machine, including a knife, a pair of grinders rotatable about substantially parallel axes and adapted to simultaneously engage with the opposite sides of said knife, a carrier for said grinders, means for moving said carrier in the direction of the length of the knife, and means for rotating said grinders independently of their engagement with the knife.
25. 9. A cloth cutting machine, including a knife, a pair of grinders rotatable about substantially parallel axes and adapted to engage with the opposite sides of said knife, a carrier for said grinders, means for moving said carrier in the direction of the length of the knife, means for rotating said grinders independently of their engagement with the knife, and means for adjusting said carrier to simultaneously adjust said grinders toward and from the plane of the knife.
30. 10. A cloth cutting machine, including a knife, a pair of grinders rotatable about substantially parallel axes and adapted to engage with the opposite sides of said knife, a rotatable carrier for said grinders, means for moving said carrier in the direction of the length of the knife, means for rotating said grinders independently of their engagement with the knife, and means for moving said carrier in the direction of the length of the knife, means for rotating said grinders independently of their engagement with the knife, and means for rotating said carrier to simultaneously adjust said grinders toward and from the plane of the knife.
35. 11. A cloth cutting machine, including a knife, a pair of grinders rotatable about substantially parallel axes, and adapted to engage with the opposite sides of said knife, a

carrier for said grinders, means for moving said carrier in the direction of the length of the knife, means for rotating said grinders independently of their engagement with the knife, and means for rotating said carrier about an axis in the plane of the knife to simultaneously adjust said grinders toward and from the plane of the knife.

12. A cloth cutting machine including a knife, a pair of grinders having substantially parallel axes at a fixed distance apart, a pinion connected to each grinder, a gear meshing with both of said pinions for simultaneously rotating them, and a member carrying said pinions and adjustable about the axis of said gear to adjust them simultaneously and to equal distances toward and from the plane of the knife.

13. A cloth cutting machine including a knife, a pair of grinders having substantially parallel axes, a pinion connected to each grinder, a gear meshing with both of said pinions for simultaneously rotating them, and a carrier for said grinders rotatable about the axis of said gear to adjust said grinders toward and from the plane of the knife.

14. A cloth cutting machine including a knife, an endwise movable shaft parallel to said knife, a member connected to said shaft and movable endwise therewith, a pair of grinders carried by said member and adapted to engage with opposite sides of the knife, and means for rotating said grinders upon the rotation of said shaft.

15. A cloth cutting machine, including a knife, a shaft substantially parallel thereto and having longitudinal and rotary movement, a pair of grinders adapted to engage with opposite sides of said knife, means for rotating said grinders upon the rotation of said shaft, and means for moving said grinders along the length of the knife upon endwise movement of said shaft.

16. A cloth cutting machine, including a knife, a shaft having rotary and longitudinal movement and disposed substantially parallel to said knife, a grinder adapted to engage with said knife, means for rotating said grinder upon the rotation of said shaft, and means for moving said grinder along the length of said knife upon the longitudinal movement of said shaft.

17. A cloth cutting machine including a knife, a grinder for engagement therewith, a member carrying said grinder, a source of power, and means connecting said member thereto for moving said grinder along the length of said knife and simultaneously rotating the grinder independently of its engagement with the knife.

18. A cloth cutting machine including a base, a vertically movable knife carried thereby, a grinder for engagement there-

- with, a member carrying said grinder, a source of power, and means connecting said member thereto for moving said grinder along the length of said knife and simultaneously rotating said grinder.
19. A cloth cutting machine, including a knife, a grinder, a carrier therefor, a shaft substantially parallel to said knife and connected to said carrier, means for moving said shaft and said carrier endwise, and power transmitting connections between said shaft and said grinder for rotating said grinder upon the rotation of said shaft.
20. A cloth cutting machine, including a knife, a grinder, a carrier therefor, a shaft extending lengthwise of said knife and journaled in said carrier, power transmitting connections on said carrier between said shaft and said grinder, and means for simultaneously reciprocating and rotating said shaft.
21. A cloth cutting machine including a knife, a grinder, a carrier therefor, a shaft extending lengthwise of said knife and journaled in said carrier, power transmitting connections on said carrier between said shaft and said grinder, and means for simultaneously rotating said shaft and moving it endwise.
22. A cloth cutting machine including a knife, a member movable lengthwise thereof, a pair of grinders, a member carried by said first mentioned member and supporting said grinders, said second mentioned member being rotatable in respect to the first mentioned member to adjust said grinders toward and from said knife, a gear carried by said first mentioned member and concentric with the axis of rotation of said second mentioned member, pinions connected to said grinders and meshing with said gear, and means for rotating said gear, said first mentioned member and the parts carried thereby being movable along the length of said knife.
23. A cloth cutting machine including a knife, a member movable lengthwise thereof, a pair of grinders, a member carried by said first mentioned member and supporting said grinders, said second mentioned member being rotatable in respect to the first mentioned member to adjust said grinders toward and from said knife, a gear carried by said first mentioned member and concentric with the axis of rotation of said second mentioned member, pinions connected to said grinders and meshing with said gear, and means for rotating said gear, and simultaneously moving it in the direction of the length of the knife.
24. In combination, a knife, a slide including oppositely disposed curved arms, a plate rotatably mounted between said arms and adjustable about its own axis in respect to said slide, and a pair of grinders carried by said plate and disposed upon opposite sides of the plane of the knife.
25. In combination, a vertically disposed reciprocating knife, a knife guard disposed in front of the cutting edge thereof, a presser-foot carried by said guard and adjustable with said guard in the direction of the length of the knife, a slide movable along said guard, a pair of grinders carried by said slide and adapted to engage with the opposite sides of the knife, a source of power and means operatively connected thereto for simultaneously rotating said grinders and moving said slide along said guard.
26. A cloth cutting machine including a base adapted to pass beneath the material to be cut, a reciprocating knife, a guard disposed in front of the cutting edge thereof and having a presser-foot normally disposed above said base, and means for locking said presser-foot to said base to prevent lateral movement of it in respect to said base.
27. A cloth cutting machine including a base adapted to pass beneath the material to be cut, a reciprocating knife, a guard disposed in front of the cutting edge thereof and having a presser-foot normally disposed above said base, and means for locking said presser-foot to said base to prevent lateral movement of said presser foot in respect to said base after said presser-foot has been lowered into engagement with said base.
28. A cloth cutting machine including a base adapted to pass beneath the material to be cut, a reciprocating knife, a guard disposed in front of the cutting edge thereof and having a presser-foot normally disposed above said base, and a member movable lengthwise of said guard and adapted to engage with said base to prevent lateral movement of said presser-foot and the lower end of said guard.
29. A cloth cutting machine having a base, a reciprocating knife, a guard in advance of said knife, a grinder movable lengthwise of said guard, and means for locking the lower end of said guard to said base.
30. A cloth cutting machine having a base, a reciprocating knife, a guard in advance of said knife, a grinder movable lengthwise of said guard, and means for locking the lower end of said guard to said base after said guard has been moved endwise into engagement with the base.
31. A cloth cutting machine having a base, a reciprocating knife, a guard in advance of said knife, a grinder movable lengthwise of said guard, and means for locking the lower end of said guard to said base, said means including a rod normally disposed within said guard and movable vertically in respect to the latter.
32. A cloth cutting machine including a base, a knife, a guard in advance of said

- knife and vertically movable in respect to said base, and a member vertically movable in respect to said guard for engagement with said base.
- 5 33. A cloth cutting machine including a base, a knife, a guard in advance of said knife and vertically movable in respect to said base, a member vertically movable in respect to said guard for engagement with said base, and a grinder for said knife mounted to move up and down along said guard.
- 10 34. A cloth cutting machine, including a base, a knife, a guard in advance of said knife, adjustable toward and from said base, a locking rod normally movable with said guard but movable in respect to said guard to lock with said base when said guard is in lowermost position.
- 15 35. A cloth cutting machine including a base, a knife, a guard in advance of said knife, a locking rod carried by said guard, means for normally preventing movement of said rod in respect to said guard, and means for lowering said guard and rod toward said base and thereafter further lowering said rod into said base.
- 20 36. A cloth cutting machine including a base, a knife, a guard in advance of said knife, a rod disposed within said guard and having a limited longitudinal movement in respect thereto, means for normally holding the rod in its upper limiting position in respect to the guard, and means for lowering the guard toward said base, said means operating to lower the rod in respect to the guard when the latter reaches its lowermost position.
- 25 37. A cloth cutting machine including a base, a knife, a presser-foot, a carrier therefor movable toward and from said base, and a locking member carried by said carrier and normally movable therewith and having a limited relative movement in respect thereto, and means for producing said relative movement when the presser-foot and carrier are in the lowermost limiting position.
- 30 38. A cloth cutting machine including a base, a knife, a presser-foot carrier movable toward and from said base, a rotatable grinder mounted to slide along said carrier, means for transmitting power to the grinder and means for preventing the transmission of power to the grinder save when the presser-foot is in a predetermined position.
- 35 39. A cloth cutting machine including a base, a knife, a presser-foot carrier movable toward and from said base, a rotatable grinder movable along the length of the knife and slideable on said carrier, means for transmitting power to the grinder and means for preventing the transmission of power to the grinder save when the presser-foot is in its lowermost limiting position,
- 40 40. A cloth cutting machine including a base, a knife, a presser-foot carrier vertically slideable toward and from said base, a grinder movable along said knife, a source of power, connections between said source and said grinders for rotating said grinder, and means rendering said connections inoperative when said carrier is moved from a predetermined position.
- 45 41. A cloth cutting machine including a base, a source of power carried thereby, a knife, a presser-foot carrier movable toward and from said base, a grinder, means for moving said grinder along the edge of the knife, and means for preventing the transmission of power to said first mentioned means save when said carrier is in a predetermined position.
- 50 42. A cloth cutting machine including a base, a knife, a presser-foot carrier movable toward and from said base, a grinder, means for moving said grinder along the edge of the knife, and means for preventing the operation of said first mentioned means save when said carrier is in its lowermost limit- 90
- 55 43. A cloth cutting machine including a base, a knife, a presser-foot carrier movable toward and from said base, a grinder, a source of power, normally inoperative power 95 transmitting connections between said source of power and said grinder for rotating the latter, and means for automatically rendering said connections operative when said presser-foot carrier is moved to a predetermined position.
- 60 44. A cloth cutting machine including a base, a knife, a presser-foot carrier movable toward and from said base, a grinder, a source of power, normally inoperative power 100 transmitting connections between said source of power and said grinder for moving the latter along the length of the knife, and means for automatically rendering said connections operative when said presser-foot carrier is moved to a predetermined position.
- 65 45. A cloth cutting machine including a base, a knife, a presser-foot carrier movable toward and from said base, a grinder, a normally disengaged clutch for reciprocating 115 said grinder along said knife, and means for automatically engaging said clutch upon the movement of said carrier to a predetermined position.
- 70 46. A cloth cutting machine including a base, a knife, a presser-foot carrier movable toward and from said base, a grinder movable along said carrier and means for locking said carrier to said base, said grinder being inoperative save when said carrier is 120 locked to said base.
- 75 47. A cloth cutting machine including a base, a knife, a presser-foot carrier movable toward and from said base, a grinder movable along said carrier, and means for si- 130

multaneously locking said carrier to said base and transmitting power to said grinder.

48. A cloth cutting machine including a base, a knife, a presser-foot carrier movable 5 toward and from said base, a grinder movable along said carrier, and means for simultaneously locking said carrier to said base and causing said grinder to move along the length of the knife.

10 49. A cloth cutting machine including a base, a knife, a grinder carrier movable in the direction of the length of the knife, a grinder carried thereby, and a shaft parallel to said knife and connected to said carrier 15 and rotatable to rotate said grinder and movable endwise to raise and lower said carrier.

20 50. A cloth cutting machine including a base, a knife, a grinder carrier movable in the direction of the length of the knife, a grinder carried thereby, a shaft parallel to 25 said knife and connected to said carrier and rotatable to rotate said grinder, and a bearing having threaded engagement with said shaft whereby the latter and said carrier are moved endwise upon the rotation of the shaft.

30 51. A cloth cutting machine including a base, a knife, a grinder carrier movable in the direction of the length of the knife, a grinder carried thereby, a shaft parallel to 35 said knife and connected to said carrier and rotatable to rotate said grinder, a bearing having threaded engagement with said shaft whereby the latter and said carrier are moved endwise upon the rotation of the shaft, and means for automatically reversing the direction of rotation of said shaft after a predetermined endwise movement.

40 52. A cloth cutting machine including a base, a knife, a grinder carrier movable in the direction of the length of the knife, a grinder carried thereby, a shaft parallel to 45 said knife and connected to said carrier and rotatable to rotate said grinder, and movable endwise to raise and lower said carrier, and means for automatically reversing the direction of endwise movement after an endwise movement to a predetermined point.

50 53. A cloth cutting machine including a knife, a grinder, a shaft substantially parallel to said knife, for rotating said grinder, said shaft being connected to said grinder and longitudinally movable to carry said 55 grinder along the length of the knife, and means for automatically reversing the direction of endwise movement of said shaft when said grinder reaches a predetermined point.

60 54. A cloth cutting machine including a knife, a shaft extending substantially parallel thereto, a grinder connected to said shaft, means for rotating said shaft and moving it endwise in one direction for a

limited distance, and means for rotating it in the opposite direction and moving it endwise in the opposite direction for a predetermined distance.

55. A cloth cutting machine including a knife, a grinder therefor, a drive shaft 70 therefor, mounted for rotating and longitudinally moving said grinder, gear transmission mechanism for rotating said shaft in either direction, and means controlled by the predetermined endwise movement of the 75 shaft for reversing said gear transmission mechanism.

56. A cloth cutting machine, including a knife, a grinder, a shaft rotatable to rotate said grinder and longitudinally movable to 80 vary the position of the grinder along the knife, gearing for transmitting power to said shaft, a member movable longitudinally to connect said gearing for rotation of the shaft in one direction and automatically 85 movable to reverse the direction of power transmission after a predetermined endwise movement of said shaft.

57. In combination, a knife, a grinder, a shaft connected thereto and mounted for simultaneous, longitudinal and rotary movement, a driving gear, two power transmitting connections between said shaft and said gear, one operating for a rotation of the shaft in one direction and the other for a 95 rotation of the shaft in the opposite direction, and a longitudinally movable rod for bringing said power transmitting connections into operation in succession.

58. In combination, a knife, a grinder, a 100 shaft connected thereto and mounted for rotary and longitudinal movement, a source of power, power transmitting connections between said source and said shaft, and a member for automatically reversing the direction 105 of longitudinal movement of said shaft after a predetermined movement in one direction and thereafter breaking the power transmitting connections after a predetermined movement of the shaft in the opposite direction. 110

59. A cloth cutting machine including a knife, a grinder therefor, a guide for said grinder, normally disengaged power transmitting mechanism for said grinder, and 115 means for simultaneously locking said guide in position and engaging said power transmitting mechanism.

60. A cloth cutting machine including a knife, a grinder therefor, a guide for said 120 grinder mounted to slide in the direction of the length of the knife, normally disengaged power transmitting mechanism for said grinder, and means for lowering said guide and automatically engaging said power 125 transmitting mechanism.

61. A cloth cutting machine including a base adapted to slide beneath the cloth to

- be cut, a knife, a grinder therefor, a guide for said grinder, normally disengaged power transmitting mechanism for said grinder, and means for sliding said guide lengthwise 5 toward said base and automatically engaging said power transmitting mechanism when said guide reaches a predetermined position.
62. A cloth cutting machine including a vertically slidable guide, a grinder vertically movable on said guide, a source of power and means for automatically connecting said source of power to said grinder to lower the latter after said guide has been 10 lowered to a predetermined point.
63. A cloth cutting machine including a vertically movable guide, a grinder vertically movable thereon, a shaft substantially parallel to said guide and connected to said 15 grinder and mounted for longitudinal and rotary movement, means for transmitting power to said shaft to move the latter downwardly, means for transmitting power to the shaft to move the latter upwardly, 20 means for automatically connecting said first mentioned power transmitting means when said guide is in lowermost position, and independent means for automatically 25 disengaging said first mentioned power transmitting means and engaging said second mentioned power transmitting means when said grinder has reached a predetermined lowered position.
64. A cloth cutting machine including a vertically movable guide, a grinder vertically movable thereon, a shaft substantially parallel to said guide and connected to said 30 grinder and mounted for longitudinal and rotary movement, means for transmitting power to said shaft to move the latter downwardly, means for transmitting power to the shaft to move the latter upwardly, means for automatically connecting said first 35 mentioned power transmitting means when said guide is in lowermost position, independent means for automatically disengaging said first mentioned power transmitting means and engaging said second mentioned power transmitting means when said grinder has 40 reached a predetermined lowered position, and means for disengaging said second mentioned power transmitting means when said grinder has completed the desired upward movement.
65. A cloth cutting machine, including a knife, a grinder therefor, manually operable means for controlling the transmission of power to said grinder to start the latter in operation, and automatic means for terminating the transmission of power after a predetermined operation of the grinder.
66. A cloth cutting machine including a cutter, a grinder therefor, power transmitting mechanism therefor and including a 45 normally disengaged gear, a guide for guiding said grinder along said cutter, and means for automatically engaging said gear upon the movement of said guide to a predetermined position.
67. A cloth cutting machine including a cutter, a grinder therefor, power transmitting mechanism therefor including a normally disengaged gear, locking means for holding said gear in disengaged position, a guide for directing said grinder along said cutter, and means for automatically disengaging said locking means upon the movement of said guide to a predetermined position.
68. A cloth cutting machine including a grinder, power transmitting mechanism therefor including a normally disengaged gear, locking means for holding said gear in disengaged position, a knife guard, and means for automatically disengaging said 50 locking means upon the movement of said guard to a predetermined position.
69. A cloth cutting machine including a knife, a grinder therefor, a knife guard, normally disengaged power transmitting 55 mechanism for said grinder, means for normally locking said power transmitting mechanism in normal position, and means for automatically unlocking said locking mechanism and engaging said power transmitting mechanism upon a predetermined movement of said guard.
70. A cloth cutting machine including a knife, a grinder therefor, a knife guard, normally disengaged power transmitting 60 mechanism for said grinder, means for normally locking said power transmitting mechanism in normal position, means for automatically unlocking said locking mechanism and engaging said power transmitting 65 mechanism upon a predetermined movement of said guard, and means for terminating the transmission of power upon a second predetermined movement of the guard.
71. A cloth cutting machine including a knife, a grinder, a source of power and power transmitting mechanism therebetween, said mechanism including means for making or breaking the transmission of power at one point and independent means for making or breaking the transmission of power at another point, said last mentioned 75 means including mechanism for effecting the movement of said grinder in either of two opposite directions along said knife.
72. A cloth cutting machine including a knife, a grinder therefor, a source of power, detachable power transmitting mechanism between said source of power and said knife, and independently adjustable power transmitting mechanism between said source of power and said grinder and including a manually shiftable element

and a second element automatically shiftable in accordance with the position of the grinder.

73. A cloth cutting machine including a knife, having a substantially straight blade portion and a portion at its upper end offset rearwardly in the plane of the knife, means connected to said offset portion for reciprocating the knife, and grinding mechanism adapted to engage with opposite sides of the knife and movable along the length thereof, said grinding mechanism being normally disposed above the blade portion and in front of the offset portion.

74. A cloth cutting machine having a reciprocating knife including a substantially straight blade portion and a connecting portion integral therewith and offset rearwardly in the plane of the blade at the upper end of the latter, a slide connected to said offset portion and an operating crank connected to said slide.

75. A cloth cutting machine including a drive shaft, a knife, a link connected to said knife, a member connected to said shaft and having an eccentric projection engaging with said link, a rod movable lengthwise through said shaft for connecting said

member to said shaft, and a spring normally tending to hold said means in operative position.

76. A cloth cutting machine including a base adapted to slide beneath the cloth to be cut, a source of power carried by said base and having a rotatable driving member, a vertically movable reciprocating cutting member and connections therebetween including two relatively movable parts and a spring between said parts for holding them in a predetermined position, but operating to relieve the rotatable parts of the jarring action caused by the reciprocating parts.

77. A cloth cutting machine including a drive shaft, a knife, a link connected to said knife, a member on said shaft having an eccentric projection engaging with said link, and a member movable lengthwise of said shaft for connecting said first named member to said shaft.

Signed at New York city, in the county of New York, and State of New York this 25th day of August, A. D. 1915.

DAVID PERLMAN.
